UNITED STATES PATENT OFFICE

2,211,123

MILKING MACHINE PULSATORT

John L. Hulbert, Poughkeepsie, N. Y., assignor to
The De Laval Separator Company, New York,
N. Y., a corporation of New Jersey

Application May 17, 1939, Serial No. 274,167

6 Claims.

(Cl. 31—61)

My invention relates to that class of automatic pneumatically operated devices, commonly called pulsators, for producing and controlling the pneumatic waves of pulsations in the teat cups of milking machines.

The object of the invention is to provide a pulsator which is of simple construction and less expensive to manufacture than those heretofore known but still having equal reliability. The object is attained by utilizing the main feature of the pulsation of my Patent No. 2,138,921, issued December 6, 1938, while modifying and simplifying its construction.

In the pulsator embodying the present invention the construction is such that the space between the valve seats of one pair connects directly through a freely open passage with a small chamber adjacent one end of the valve carrier, while the space between the valve seats of the other pair connects, through a restricted passage with a large air chamber freely communicating with a small chamber adjacent the other end of the valve carrier; the valve carrier being positioned to reciprocate in a vertical direction. By this construction and arrangement it is insured that, when not in operation, the valve carrier will always be at one end of its stroke ready for a start, thereby eliminating the special starter valve and ports of the pulsator of my said patent and I eliminate one of the two constricted passages of the said patented pulsator and the required cleaning device therefor.

In the accompanying drawing of my improved pulsator, Fig. 1 is a vertical sectional view showing the conditions with the valve carrier at the lower end of its movement, and Fig. 2 is a similar view showing the conditions with the valve carrier at the upper end of its movement.

1 is a pulsator body having a vertical bore 2 in which a loose fitting valve carrier 3 reciprocates and around which are two upper poppet valve seats 4 and 5 and two lower poppet valve seats 6 and 7. Around the valve carrier are two poppet valves, an upper one 8 adapted to contact with the seats 4 and 5 and a lower one 9 adapted to contact with the seats 6 and 7. Between and at both sides of the valves the carrier is reduced in size to permit easy flow of air around and along it. Around the upper end of the bore 2 there is a small chamber 10 across which extends an impervious flexible partition 11 and at the lower end of the bore there is a similar chamber 12 and a similar partition 13.

An atmospheric inlet 14 communicates with the central part of the bore 2 and a vacuum pas-

sage 15 communicates with the bore beyond the valve seat 4 and the seat 7.

The space between the valve seats 4 and 5 is in free communication with a nipple 16 adapted to receive a rubber tube for connection with the pulsation chambers of a pair of teat cups 17 and is in communication, through a restricted orifice 18, of the type shown in my earlier Patent No. 2,096,807, issued October 26, 1937, with an air chamber 19, of comparatively large volume, in the upper part of the body, which, through chamber 10, communicates with the more distant side of the flexible partition 11.

The space between the valve seats 6 and 7 is in free communication with both the nipple 20, adapted to receive a rubber tube for connection with the pulsation chambers of two teat cups 21, and through a channel 22, with the more distant side of the lower flexible partition 13.

With the valve carrier 3 and valves 8 and 9 in the position shown in Fig. 1, and the passage 15 connected with vacuum, air, at atmospheric pressure, can flow quickly from the inlet 14 past the valve seat 6 then through nipple 20 to teat cups 21 and through channel 22 to the far side of the partition 13, which will be thereby pushed against the lower end of the carrier 3 and will tend to move it upward. This upward movement will be resisted by atmospheric pressure on the upper side of valve 9 and by the partition 11 which at first is held down by pressure from the chamber 19. At the same time air is exhausted quickly from the teat cups 17 through the nipple 16 and slowly from the chamber 19 through the orifice 18 past the valve seat 4 and into the vacuum passage 15.

As the pressure in chamber 19, and through the partition 11, against the upper end of the valve carrier 3, slowly reduces, it eventually becomes so weak that the partition 13, under the influence of full atmospheric pressure, is able to move the carrier upward. As soon as the valve 9 leaves the seat 7 air at atmospheric pressure rushes around its edge and increases the pressure below it so that the carrier moves quickly to the upper end of its stroke, as shown in Fig. 2.

Air is now quickly exhausted past valve seat 7 to passage 15 from the nipple 20, cups 21 and, through channel 22, from the under side of partition 13 which then has equal pressure on both its sides because its upper side is, through leakage around the lower end of the loose fitting carrier, in constant communication with passage 15. Air from inlet 14 quickly fills nipple 16 and teat cups 17 and flows slowly through orifice 18 into

chamber 19 and presses the partition 11 against the upper end of the carrier. As the pressure builds up it finally becomes strong enough to overcome the resistance due to atmospheric pressure 5 sure against the under side of valve 8 and forces the carrier down to the position shown in Fig. 1 and the cycle is repeated. In this movement air rushing around the edge of valve 8 when it first leaves seat 4 increases the downward force so that 10 the movement is completed almost instantaneously.

In a manner similar to that shown in my aforementioned Patent No. 2,138,921 the valve carrier is guided by the walls of the bore but fit so loosely that there is no danger of its being stuck by dust, 15 and friction is negligible. The air tight valve action is all by poppet valves which are so proportioned that when the valves once break away from their seats the resistance to movement is so greatly reduced that the valves and carrier complete 20 their stroke almost instantaneously.

The sizes of the exposed ends of the carrier may be so proportioned that they compensate for its weight and cause the pauses at the two ends of its movement to be of equal time length.

25 What I claim and desire to protect by Letters Patent is:

1. In a milking machine pulsator, the combination of a body member having two pairs of spaced apart valve seats, a valve carrying member reciprocable in the body member, poppet valves carried by the carrier member, one for each pair of valve seats, sources of high and low pressure, air chambers at opposite ends of said carrier and air passages communicating with the 30 respective chambers adapted, at either end position of the carrier, to be connected, by said valves, one with the source of high pressure and the other with the source of low pressure, to thereby effect the shift of the carrier toward its 35 other end position, one of said passages being relatively restricted and the other relatively free, so that the shift in one direction is effected by a rapid flow of air into one chamber and a slow exhaust from the other while the shift in the 40 other direction is effected by a rapid exhaust from the first named chamber and a slow flow of air into the second chamber.

2. In a milking machine pulsator, the combination with a body having a bore with poppet- 50 valve seats, a member reciprocable within said bore, poppet valves carried by said member and adapted to cooperate with said seats, air chambers at opposite ends of the bore, flexible non-permeable walls closing the bore from the 55 respective air chambers and adapted to press against the opposite ends of said member, sources of high and low pressures, and passages adapted when the member is at either end of the bore to connect the near chamber with the source of 60 high pressure and the far chamber with the source of low pressure, one of said passages being relatively restricted so that the air flow into and out of the same is comparatively slow, the other passage being relatively unrestricted so that the 65 air flow into and out of the same is relatively rapid.

3. In a milking machine pulsator, in combination, a body having a bore with poppet-valve seats therearound, an air chamber at each end 70 of said bore, passages communicating with the respective chambers, flexible non-permeable walls closing the bore from the respective air chambers, a member reciprocable in said bore, poppet valves carried by said member and adapted to cooperate 75 with said valve seats and, in the reciprocation of

said member, to connect, through the passage communicating therewith, the chamber toward which said member has moved with a source of high pressure and, through the passage communicating therewith, the chamber from which 5 said member has moved with a source of low pressure, the two passages being relatively restricted and unrestricted.

4. In a milking machine pulsator, the combination with a body having a vertically extending bore with poppet valve seats, a member reciprocable within said bore, poppet valves carried by said member and adapted to cooperate with said seats, chambers at opposite ends of the bore, flexible non-permeable walls closing the bore 15 from the respective air chambers and adapted to press against opposite ends of said member, sources of high and low pressure, and passages adapted when the member is at either end of the bore to connect the near chamber with the source 20 of high pressure and the far chamber with the source of low pressure, the passage connecting with the upper air chamber being relatively restricted and the passage connecting with the lower air chamber being relatively unrestricted, 25 the upper chamber being of comparatively large volume and the lower chamber being of comparatively small volume.

5. In a milking machine pulsator in combination a body having a vertical bore with two 30 pairs of poppet valve seats one above and one below the center of length of the bore, a flexible impermeable partition at each end of the bore, an air chamber in communication with the more distant side of the upper flexible wall and communicating therewith a restricted passage leading to the space between the upper pair of valve seats, a relatively unrestricted passage leading from the space between the lower pair of valve 35 seats to the more distant side of the lower flexible 40 partition, a source of higher pressure in constant communication with the bore between the pairs of valve seats, a source of lower pressure in communication with the two portions of the bore beyond the valve seats, and a valve carrier reciprocable in the bore and having two poppet valves adapted when in the lower position to close communication from the source of lower pressure and open communication from the higher pressure to the space between the lower pair of valve 50 seats, whereby the higher pressure is quickly communicated to the more distant side of the lower flexible wall to press it against the lower end of the valve carrier, and to close communication from the higher pressure and open communication from the lower pressure to the space between the upper pair of valve seats, whereby the air chamber and space above the upper flexible wall are slowly exhausted until the lower flexible wall forces the valve carrier to the upper 55 position, whereby the connections will be reversed and air will be quickly exhausted from the space beyond the lower flexible wall and slowly fed to the air chamber and the space beyond the upper flexible wall.

6. In a milking machine pulsator in combination, a valve carrier with two poppet valves therearound, a body having a bore and two pairs of valve seats therearound, said bore adapted to receive and by its smaller diameter portions 70 loosely guide the carrier with its valves each reciprocable between the two valve seats of the corresponding pair of valve seats, an impermeable flexible partition across each end of the bore, the body having a relatively unrestricted passage of 75

5 relatively small volume from the space between the valve seats of one pair to the more distant side of one flexible partition, the body having a chamber of relatively large volume communicating with the more distant side of the other flexible partition, and another passage of restricted cross section leading from the space between the valve seats of the other pair to said chamber, a higher fluid pressure feed to the bore at its center

of length, and a communication from the bore beyond each pair of valve seats to a source of lower fluid pressure, the passages and valves being so arranged that, when the carrier is at either end of its movement, it causes a pressure differential tending to force it to the other end of its movement.
